UNITED STATES PATENT OFFICE.

WALTER JAMES GASKELL, OF PHILADELPHIA, PENNSYLVANIA, ASSIGNOR OF ONE-HALF TO CLARKE D. HUNTER, OF PHILADELPHIA, PENNSYLVANIA.

LADY'S BANDEAU AND PERMANENT WAVE.

Application filed April 20, 1927. Serial No. 185,288.

The present invention relates to the art of permanent waving of hair, and at present it is generally customary to apply permanent waves in the hair by the application of electrical heat. Such process in general consists in combing the hair and twisting or wrapping a number of strands of hair at different locations on the head about an electrical heating implement, the wrapping beginning commenced about an inch or inch and a half from the scalp. This process has many disadvantages. In the first place due to the wrapping commencing an inch or inch and a half from the scalp, the hair, though it is permanently waved, lies close to the scalp, when the hair is dressed and arranged. Secondly it is well known that electrical permanent waving of hair takes all the life from the hair, practically kills it, makes it brittle and removes the oil, and very often the hair becomes relatively short due to the strands breaking at various points between the hair terminals and where the permanent waving commences. It other words constant waving of the hair in five to ten years, causes the hair to have uneven lengths of strands, and what strength may be procured from the roots is of very little good, as the hair where it is permanently waved is not of a character to absorb the strength, and thereby rendering the hair incapable of being rejuvenated. In fact the main idea in the present everyday process of permanent waving, consists in waving or bending the hair at a substantial distance beyond the follicles or roots of the hair.

The present invention and process resulting during use of this invention deviates primarily from the old method as above identified, in the fact of growing a permanent wave in the hair, by bending the hair immediately at the follicles or roots. To carry out this thought and idea it is the aim to reverse the position of the hair beyond and commencing at the root follicles, causing the hair to fluff and position away from the scalp after the removal of the bandeau, and after the hair has increased in length a permanent wave grows in the strands of hair, giving the hair when dressed a beautiful and natural appearance, not only being pleasing to the eye, but particularly softening the features of the wearer, which as is

well known is not the case in permanent waving of the hair by electrically heating implements.

In addition to these results the present invention and its process in time produces healthier hair and a healthier scalp, strengthening both, permitting air to reach the scalp, which not only permits the scalp to thrive and fatten but also causes the hair to attain natural electrical tension, enabling the hair to be well dressed, to naturally conform to and beautify the wearer's features and general appearance. The fundamental idea in the present invention is to grow a permanent wave in the hair, by bending the root follicles, in order to produce a natural permanent wave.

To perform this result, the invention has for its purpose to provide an improved bandeau, which when applied together with a proper application of a suitable oil dressing (which softens the texture of the hair), the bandeau being worn over night or for a sufficient period during the day preferably as over night wearing tends to disarrange the position of the bandeau, bends the root follicles, which in a relatively short period of time causes a permanent waving to be grown in the hair.

Another purpose is to provide a bandeau of this kind consisting of a band engaged about the back portion of the head and brought forward over the sides of the head, with an extension tongue band merging from the band at the back and positioned over the crown of the head, with the terminals of both bands joined at a common junction, the strands of hair having been previously thoroughly combed up at the back and sides in such wise as to bend the strands of the hair immediately at the root follicles.

It is to be understood that prior to the application of the bandeau and the combing of the hair upward, the user of this process of permanent waving, applies a suitable oil dressing, the dressing being rubbed into the scalp and into the root follicles, a substantial portion thereof being also applied to the hair proper, which results in softening the texture of the hair and at the same time strengthening the scalp and the hair as well as the root follicles.

Still another purpose is to provide a ban-

deau made of any suitable fabric material preferably porous cloth with elastic insets so arranged in the bands as to provide for substantial tension on the head and thereby hold the hair bent at the root follicles and as a result causing the hair to grow or train upward, the whole scheme consisting in a reverse training of the hair, hence causing a substantial permanent wave to grow in the hair beyond the root follicles.

A further purpose consists in constructing the insets of substantial elastic material, preferably porous elastic material of a texture suitably greater than the texture of the bands themselves, permitting the elastic portions of the insets to not only yield properly, but to afford a substantial tension on the hair to hold the hair in bent position at root follicles of the strands, it being noted that the insets are capable of yielding in direction with the length of the bands, and incapable of yielding in directions at right angles thereto, so as to hold the strands of hair at the desired position causing a substantial permanent wave to result, when the hair has received the proper growth.

It is to be understood that the particulars herein given are in no way limitative, and that while still keeping within the scope of the invention, any desired modification of details and proportions may be made in the construction of the bandeau and the method resulting from the use of the bandeau.

The invention comprises further features and combination of parts to be hereinafter set forth, shown in the drawings and claimed.

In the drawings:

Figure 1 is a view of a lady's head, showing the application of the improved permanent wave producing bandeau as applied.

Figure 2 is a sectional view on line 2—2 of Figure 1 through the permanent wave bandeau, indicating the surface of the scalp and showing where the strands of hair are bent at the root follicles, so that when the hair has received a substantial growth, the hair will have had grown therein a substantial permanent wave.

Figure 3 is a view of a head showing the character of permanent wave as a result of the use of this particular bandeau and the process obtained thereby.

Figure 4 is a view of the bandeau showing it in the position it assumes while on the head, but the head eliminated, in other words illustrating a skeleton view of the bandeau.

Figure 5 is a view of the bandeau flattened out, showing all of its structural features.

Referring to the drawings: 1 identifies the bandeau as a whole, which consists of the main band 2 which engages with the back of the head, with the end portions 3 brought

forward in contact with the sides of the head above the ears, with the terminals fastened together at 4 by any suitable means preferably straps 5 and buckles or the like 6. The lower edges of the end portions 3 of the band 2 are cut away arcuately to make room or provide space for the accommodation of the ears. However should the end portions with their arcuately cut away parts lie over the ears (provided the latter are overly large or positioned a little different than others), they will not interfere with the desired result, namely that of holding the hair close to the head. The fact is an operator in applying a bandeau to a head for permanent waving may observe that the ears are more or less protruding in which case the operator will purposely engage the band over the ears to flatten them to the head, as this is an essential desire of many of the female sex.

The lower portion of the band 2 at the rear has an elastic inset, made of any suitable material, preferably elastic porous cloth, and the elasticity of this inset 7 is in a direction with the length of the band, intensifying the tension of the band on the head and insuring holding the hair close in contact with the head.

As is understood the hair is previously reversedly combed, in other words combed up tight against the scalp, the band 2 then being applied.

To further insure tension of the bandeau to the head, the end portions 3 of the band 2 are provided with insets 8, which are also constructed of any suitable material preferably elastic porous cloth, and as with the inset in the back their elasticity, is in a direction with the length of the band. These insets are connected to the band in any suitable approved manner, possibly by means of stitches as indicated at 9, the edge portions of the insets consisting of a closer weave of the elastic porous cloth than the bodies of the insets, the difference of weave being indicated as illustrated, and thereby providing a substantial body, to which the cloth of the band may be attached without undue tearing. These insets have their marginal edges constructed to avoid frayed or selvage portions.

Merging preferably integrally from the band 2 to the back is a head crown engaging band 10 which is of a substantial size, sufficient to conform and fittingly engage with the crown of the head. This band 10 extends forward over the crown and down over the forehead and is connected at the common junction 4, that is where the terminals of the end portions of the band 2 connect. This connection is assured by any suitable means, preferably the same fastenings as used for the terminals of the end portions of the band 2. The band 10 is also

provided with inset 11 similar in construction to the insets in the band 2. The fact is this inset 11 is also constructed of any suitable material preferably elastic porous cloth, identical in construction and design with those in the band 2. In a like manner the elasticity of the inset 11 is also in a direction with the length of the band 10. The purpose of the inset 11 is likewise similar to that of the insets in the band 2, namely to hold the hair tight against the crown of the head, in fact in contact with the entire area of the top of the head. The insets cause the bandeau to shape or conform to and fittingly engage with the head, so as to insure holding the strands of hair in their reverse positions.

Prior to positioning the band 10 and subsequently to arranging the band 2 the strands of hair on the top of the head are arranged reverse to the positions the strands of hair previously assumed. In other words if the wearer parts the hair on the right hand side combing the longer strands to the left, the strands to the left are reversed to the right prior to positioning the band 10, while the strands to the right are positioned to the left, previous to the positioning the band 10. After removing the bandeau, it having been worn a substantial period of time, and the hair dressed as desired by the wearer, the hair will fluff away from the scalp, assuming a natural wave, one more fitting to the features of the wearer and beautifying the face, and thereby softening the general appearance of the head and face. Each time the bandeau is applied and then removed the strands of hair at their root follicles receive an additional bend, the hair in the meantime having grown a certain distance, in this way a permanent wave is grown in the strands of hair by the bending of the strands at their root follicles, that is by a reverse training of the hair. Prior to each application of the bandeau a requisite quantity of any suitable oil dressing is thoroughly massaged into the scalp and into the root follicles, as well as into the hair in general, and thereby softening the texture of the hair. The marginal edge of the entire bandeau is finished off as at 12, since it is preferably made of a suitable porous knit cloth, so as to avoid frayed portions or selvage, and thereby provide a very essential and suitable article of manufacture, such as a permanent wave bandeau.

By applying the bandeau periodically variably it is possible to grow into the hair waves of varying lengths, that is when applied at conjunction with reversed training of the hair.

The invention having been set forth, what is claimed is:

1. A bandeau for permanent waving comprising a dominant band to fit around the

head from the back forward of and engaging with the sides of the head and provided with means at its adjacent terminals for tightening and holding the band in position, said dominant portion of the band having an auxiliary crown engaging band merging therefrom to conform to and fittingly engage with the crown of the head, with its forward terminal extending down over the forehead and joined with the terminals of the side portions of the dominant band. 70 75

2. A bandeau for permanent waving consisting of dominant and auxiliary bands, one to conform to and engage about the head from the back to the front around the sides thereof, with the other conforming to and fittingly engaging with the crown of the head, and means for uniting the terminals of the bands at a common junction. 80

3. A bandeau for permanent waving consisting of dominant and auxiliary bands, one to conform to and engage about the head from the back to the front around the sides thereof, with the other conforming to and fittingly engaging with the crown of the head, and means for uniting the terminals of the bands at a common junction, and means in the bands for insuring elasticity in directions with the bands, for creating substantial tension, to hold the hair in reversed training flattened against the head. 85 90 95

4. A bandeau for permanent waving consisting of dominant and auxiliary bands, one to conform to and engage about the head from the back to the front around the sides thereof, with the other conforming to and fittingly engaging with the crown of the head, and means for uniting the terminals of the bands at a common junction and means in the bands for insuring elasticity in directions with the bands, for creating substantial tension, to hold the hair in reversed training flattened against the head, said last named means consisting of insets of elastic porous material with a substantially close marginal weave, and means for fastening said closely woven margin to the material of the bands. 100 105 110

5. A process of permanently waving hair, consisting of reversely training the hair by 115 combing it upward, bending the strands at the root follicles, reversely training the hair on the crown of the head, conforming a bandeau to and fittingly engaging it over the reversed trained hair, retaining the strands of hair bent at their root follicles for a substantial period. 120

6. A process of permanently waving hair, consisting of reverse training of the hair by combing it upward, bending the strands at the root follicles, reversely training the hair on the crown of the head, conforming a bandeau to and fittingly engaging it over the reversed trained hair, retaining the strands of hair bent at their root follicles for 125 130

a substantial period, and tensioning the bandeau and hence insuring a tighter contact of the hair with the scalp of the head.

7. A process of permanently waving hair consisting in massaging an oil dressing into the scalp and the root follicles of the hair and into the hair proper, reversely training the hair by combing it upward, bending the strands at the root follicles, reversely train-

ing the hair on the crown of the head, con- 10 forming a bandeau to and fittingly engaging it over the reversed trained hair, retaining the strands of hair bent at their root follicles for a substantial period.

In testimony whereof he affixes his signature hereto. 15

WALTER JAMES GASKELL.
